CLAIM

The ornamental design for a firefighter ring, as shown and described.

DESCRIPTION

FIG. 1 is a front, isometric view of a firefighter ring showing our new design;

FIG. 2 is a top view thereof;

FIG. 3 is a bottom view thereof;

FIG. 4 is a first side view thereof;

FIG. 5 is a second side view thereof;

FIG. 6 is a front view thereof; and,

FIG. 7 is a back view thereof.

The broken line portion of the figures is included to show unclaimed subject matter only and forms no part of the claimed design.
